FIRE EXTINGUISHER

Josef Neumann, Brunn, Czechoslovakia

Application January 3, 1935, Serial No. 204
In Czechoslovakia January 24, 1934

2 Claims. (Cl. 169—28)

This invention relates to an apparatus for extinguishing fire, in which a vat filled with a quenching fluid is discharged by the combustion of a readily ignitable member. The said invention consists in that a vessel is located within the said vat, which vessel is filled with gunpowder or the like, on the inflammation of which a considerable pressure above atmospheric is produced and the quenching fluid driven out with great strength. The said device is intended, in particular, for the quenching of fires caught by a carburettor of an automobile.

It is known to provide automatically acting quenching devices in which shot-firing cables are used, so that it will take much time until the shot-firing cable ignited by the fire actuates the device.

Furthermore, automatically acting quenching apparatus provided with mechanical devices such as, for example, springs under tension which will be released by the burning-through of a cord, have been employed. In such apparatus either a cartridge which slowly forces the quenching fluid from the apparatus is operated, or a glass vessel is broken from which the quenching fluid is free to flow out. Also these apparatus take relatively long time until the quenching fluid acts, and, therefore, cannot prevent a partial combustion of the endangered devices.

Moreover, these known devices present the disadvantage that a metallic mechanical device will, through the action of damp air or gases, undergo certain alterations on its surface, whereby their release will become unreliable. Also the constant shocks that occur in automobiles will act unfavorably on the said quenching devices, the cords retaining the springs under tension getting worn out whereby the device is uselessly actuated. Since it is difficult to seal metallic vessels that contain the quenching fluid, either the said quenching fluid will evaporate, or if quenching powders are used, such powders will become damp, so that it will to a considerable extent lose its quenching capacity.

All these disadvantages are entirely removed by the object of my invention. This is attained by the absence of any mechanical device whatever as well as by the absence of a shot-firing cable, the whole device being made without the use of any metal but solely of artificial resin or the like, which has the advantage of not requiring any sealing or packing members, due to the fact that the individual parts of the container may be assembled to form a uniform piece by coating the threads with some solvent, so that

the joints are directly pasted together and the use of any sealing material is avoided. Thus, neither can the quenching means escape, nor can it undergo an alteration in the course of time. The forcing out of the quenching means takes place due to the fact that a portion of the quenching device is made of a readily inflammable material such as celluloid which will be directly ignited by the fire kindled. This ignitable member contains gunpowder or the like, the combustion of which will produce a considerable pressure above atmospheric, due to which the quenching fluid will be driven out with great strength.

If the apparatus is used for the purpose of avoiding carburettor fires in automobiles, it should be mounted above the carburettor so that the bottom of the apparatus is turned toward the burning area. On the breaking-out of a fire the readily ignitable shot-firing fuse that ends at the said area will therefore be at once ignited, so that a momentary effect of the quenching device will take place. Other advantages of the use of artificial resin over the use of metal are the small weight and measurements of the device, which both are apt to favorably influence the price of the apparatus.

In the drawing, an example of an embodiment of the invention is illustrated.

Fig. 1 is a longitudinal section of the quenching device according to the invention; and

Fig. 2 shows the atomiser which forms a part of the quenching device.

1 is a container made of artificial resin or the like. The said container is sealed at the top thereof by a cap 2 threaded on, and, by means of a fluid, pasted onto member 1. At the bottom of the said container a bottom plate 3 made of a readily inflammable material such as celluloid is tightly fitted in. The said container is almost completely filled with a quenching fluid, such as carbon tetrachloride, ethyl bromide or the like. These quenching fluids are chemically neutral to artificial resin and celluloid, so that no alterations can take place by the action of these chemicals. Into the bottom plate a small tube 4 is inserted, which, at least at its lower part, that is, where it is fitted into the bottom plate, is made of a readily inflammable material, such as, for example, celluloid. The upper portion of the small tube, which, preferably, is flared at 5, may be made of a less readily inflammable material. The tube is filled with gunpowder or the like. At the bottom of the container a conical extension 6 is mounted, say, by means of screws. In order to obtain efficient atomization of the quenching fluid, a plate 9 is

fastened to the bottom of the container 1, which plate is formed with a star-shaped cut or blank. The said plate is held by means of a ring 10. The container is appropriately fastened at the area 8 where it is to be protected from fire. For this purpose may be used a fastening means which encompasses the container and can be tightened and fastened by means of a bolt 8.

Structural modifications of the device described 10 may be made without abandoning the scope of the present invention. Thus, the bottom plate 8 may be made of artificial resin instead of celluloid and may be all of a piece with member 1 so that, if desired, only the small tube 4 with the flare 5 is made 15 of an inflammable material, such as celluloid. In either case, however, the effect will be the same, since, due to the broken-out fire, the lower portion of the tube 4 will be burnt and, thereby, the gunpowder ignited and the quenching means 20 driven out.

It is to be understood that the device according 25 to the invention is not limited to the use in automobiles, but may be employed with advantage in explosion motors in general, as well as in cinema-cabins or places for storing ignitable material.

What I claim is:—

1. In a fire extinguisher, a molded container formed of a synthetic resin, an extinguishing ma-

terial in said container, a weakened end wall integrally formed in said container, said wall having as an insert a tube projecting therethrough and extending into the interior of said container, an explosive material carried by the inner end of said tube, fuse means extending through said tube and communicating with said explosive material, and a highly inflammable outer end portion on said tube contacting said fuse means.

2. In a fire extinguisher, a molded container 10 formed of a synthetic resin, a volatile extinguishing liquid substantially filling said container, a weakened end wall integrally formed in said container, said wall having as an insert a tube projecting therethrough and extending into the interior of said container, an enlarged chamber 15 formed on the inner end of said tube and surrounded by said liquid, an explosive material confined in said chamber, fuse means contained in said tube and communicating with said explosive, 20 a highly inflammable material comprising the outer end of said tube and contacting said fuse means, and a cap of said synthetic resin forming a closure for the other end of said container and integrally secured therewith by a homogenous 25 bond.

JOSEF NEUMANN.
